FLOOR MAT

Joseph Gaylord Chapman, Columbia, Mo.

Application August 20, 1948, Serial No. 45,262

2 Claims. (Cl. 154—49)

1

My invention relates to floor mats, and more particularly to floor mats having resilient characteristics, whereby to protect the feet of users from fatigue. Specifically, the mat according to the invention relates to floor mats adapted to be used by workers the nature of whose jobs requires that they stand on their feet substantially the entire working day. Thus, the mat according to the invention is specifically adapted for use by barbers, dentists, sales personnel, machine operators, and others who seldom have a chance to sit down.

With the foregoing in view, it is an object of my invention to provide an improved resilient floor mat.

A further object is to provide an improved resilient floor mat which includes a flat member of cushioning material and a cover member for the same providing a wear surface, said cover member being readily detachably connected to said flat member.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing:

Figure 1 is a plan view of a mat according to the invention, parts being broken away to show the interior thereof;

Figure 2 is an edge elevation of the mat of Figure 1;

Figure 3 is an enlarged fragmentary vertical sectional view taken substantially on the plane of the line 3—3 of Figure 1;

Figure 4 is a bottom plan view of the mat on a reduced scale, with the cushioning insert removed;

Figure 5 is a plan view of the cushioning insert apart from the rest of the structure, parts being broken away;

Figure 6 is an enlarged vertical sectional view taken substantially on the plane of the line 6—6 of Figure 1.

Cushioning floor mats are well known and generally comprise either a body of cushioning material alone, or a body of cushioning material integrally connected to a top layer providing a wear surface. In the first instance, the cushioning material being relatively soft quickly wears out, whereby it must be replaced. In the second instance, when the wear surface finally wears out,

the entire mat must be replaced. These difficulties are overcome by the mat according to the invention. Referring specifically to the drawing, wherein like reference characters have been used throughout the several views to designate like parts, 10 designates generally the cushion-providing portion of the mat which comprises a substantially flat member of laminated construction. Thus, the cushioning member 10 comprises an upper and relatively thick layer of any suitable cushioning material, such as sponge rubber, and a relatively thin backing sheet 12 of relatively rigid material, such as hard rubber. Preferably, the cushioning layer 11 and the backing sheet 12 are integrally connected together in any suitable manner, as by the adhesive 13.

To protect the upper surface of the cushioning layer against wear, I have provided a relatively flat cover 14, the under surface of which is formed with a cavity 15 which is complementary to the cushioning member 10 and which is adapted to receive the latter therein with a close fit. Outwardly of the recess 15, the cover 14 is provided with a relatively wide marginal portion 16 and a similar marginal portion 17 is provided laterally inwardly of the recess. The upper surface of the outer marginal portion 16 may be downwardly beveled, as at 18. The purpose of the marginal portions 16 and 17 is to give rigidity to the marginal portions defining the recess 15, whereby the same is unlikely to be distorted in use. At the same time, such marginal portions give weight to the cover and tend to maintain the same flat against the floor, whereby the cushioning member 10 is prevented from escaping from the recess 15. In this connection, it should be noted that no particular means for connecting the cushioning member 10 to the cover 14 are contemplated other than the frictional engagement of the side walls of the recess 15 with the side edges of the insert 10.

The upper surface 19 of the cover 14 is substantially flat, but is preferably formed with a plurality of grooves 20, best seen in Figure 6 and Figure 1, which permits the circulation of air beneath the feet of the user and to some extent cool the feet.

From the foregoing, it is apparent that the mat according to the invention will last indefinitely in so far as the cushioning member 10 is concerned, as new covers 14 may be furnished at relatively low cost as soon as they are worn out. The particular embodiment of the mat shown on the drawing is of segmental construction, whereby it is readily adapted to fit around the pedestal

of a barber or dentist chair, or the like. However, it should be understood that the mat may be made in any shape, whereby it may be used by machine operators, sales clerks, or other persons requiring such a mat.

Thus, while I have shown and described what is now thought to be a preferred embodiment of the invention, it is to be understood that the same is susceptible of other forms and expressions. Consequently, I do not limit myself to the precise structure shown and described hereinabove except as hereinafter claimed.

I claim:

1. In a cushion floor mat, a solid semicylindrical segment fabricated of hard rubber and having one face adapted to rest upon a supporting surface, the straight edge of said segment being provided with a semicylindrical cutout having its periphery disposed in spaced relation with respect to the periphery of said segment, the marginal portion of the other face of said segment being uniformly tapered inwardly and upwardly from said one face of said segment to the other face thereof, there being a plurality of groups of radially extending slots provided in the remaining portion of said other face of said segment for the circulation of air beneath the feet of a user, said one face of said segment being provided with a recess extending inwardly therefrom and terminating at a point adjacent to and spaced from the other face of said segment, the bounding walls of said recess being disposed in substantial alignment with the meeting edges of the marginal and remaining portions of said other face of said segment, and cushioning means shaped complementary to said recess and frictionally engageable with the bounding walls thereof.

2. In a cushion floor mat, a solid semicylindrical segment fabricated of hard rubber and having one face adapted to rest upon a supporting surface, the straight edge of said seg-

ment being provided with a semicylindrical cutout having its periphery disposed in spaced relation with respect to the periphery of said segment, the marginal portion of the other face of said segment being uniformly tapered inwardly and upwardly from said one face of said segment to the other face thereof, there being a plurality of groups of radially extending slots provided in the remaining portion of said other face of said segment for the circulation of air beneath the feet of a user, said one face of said segment being provided with a recess extending inwardly therefrom and terminating at a point adjacent to and spaced from the other face of said segment, the bounding walls of said recess being disposed in substantial alignment with the meeting edges of the marginal and remaining portions of said other face of said segment, and cushioning means shaped complementary to said recess and frictionally engageable with the bounding walls thereof, said cushioning means comprising a thin backing sheet having one face adapted to rest upon said supporting surface, and a thick cushioning member resting upon said backing sheet and secured thereto.

JOSEPH GAYLORD CHAPMAN.
